CLAIM

The ornamental design for a pet dental chew, as shown and described.

DESCRIPTION

FIG. 1 is a perspective view of a pet dental chew showing a new design;

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

The middle portion of the pet dental chew of FIGS. 1-7 shown broken away and bracketed indicates indeterminate length and forms no part of the claimed design.

The broken line portion of FIGS. 1-7 is included to show unclaimed subject matter only and forms no part of the claimed design.

1 Claim, 2 Drawing Sheets
